VIBRATOR

Henry M. Dressel, Chicago, Ill., assignor to Oak Manufacturing Company, Chicago, Ill., a corporation of Illinois

Application April 29, 1939, Serial No. 270,877

14 Claims. (Cl. 200—90)

This invention relates to vibrators and particularly to vibrators operating at frequencies high in comparison to the frequencies in use at present.

At the present time the greatest field for use of vibrators is in connection with the power supplies of radio receivers or transmitters, particularly for automobiles and air craft. A low voltage direct current from a suitable battery may be interrupted by a vibrator and stepped up by means of a transformer to a satisfactory voltage level. Thereafter the alternating currents may be rectified and filtered or treated in any other desired manner. In most instances however these alternating currents are rectified and filtered, the latter being accomplished by the use of chokes and condensers. As is well known, the size, weight and cost of the transformers and filtering equipment is substantially reduced with increase 20 in frequency of interrupted current. Hence, an increase in the cost of the vibrator itself may be tolerated if the resulting frequency is sufficiently high so that the overall cost of the entire system is reduced.

This invention attains the object of higher operating frequencies in a manner different than heretofore used. The invention utilizes a relatively weak spring and high loading at the contacts. The energy is fed into a part having substantially small amplitude. In fact this part—the armature—is connected to the movable contact by a rigid member so that, to use an electrical analogy, the coupling is almost perfect. However, to store energy in the vibrating part of the system, a separate spring and weight are used which only comes into play after the device has started to operate. This separate spring is stiff enough to give, in combination with the loading, a high frequency operation without requiring a high 35 starting force.

Suitable contact action is secured by having push-pull operation on the armature. Two magnetic systems are provided which operate on the armature alternately on each side of its neutral position. By virtue of inherently easy starting due to the weak reed and a polarizing action in the magnetic system, effective starting is secured. In fact, the reduced armature amplitude and its substantially constant range permit a closer 50 position of the armature to the poles so that the armature operates in an intense magnetic field. Because the supporting reed is weak and may be considered, in some respects, as a pivot it is possible for the movable contact to have substantial 55 amplitude without reed breakage.

The vibrator of the present invention is of the shunt coil type wherein each magnetizing coil is alternately shunted out. In combination with a center-tapped transformer primary it is particularly desirable and effective. The present-day type of vibrator having a single driving shunt coil and operating with a center-tapped transformer winding introduces an electrical asymmetry which is highly objectionable. Thus one part of the primary is in series with the driving coil when the contacts are open whereas the other half of the primary is directly in the battery circuit. In the invention described herein, this is eliminated so that a perfect balance between the halves of the primary winding is possible. The entire system including the vibrator and transformer has what might be termed a neutral electrical axis with everything symmetrical around it.

Referring to the drawings:

Figure 1 is an elevation partly in section of a vibrator;

Fig. 2 is a sectional view along line 2—2 of Fig. 1;

Fig. 3 is a detail of the vibrator frame;

Fig. 4 is a detail of the vibrating element of the vibrator;

Fig. 5 is an exploded view of the vibrator and its parts with certain portions broken away; and

Fig. 6 is a circuit diagram of the vibrator.

The frame of the vibrator may take on a variety of forms but is preferably made in the form shown in Fig. 3 for the reason that the frame may be made out of one piece in a simple stamping operation. The frame has a generally U-shape and comprises a bottom portion 10 with a pair of upstanding sides 11 and 12. Sides 11 and 12 may be provided with windows 13 and 14 and terminate in reduced extensions 15 and 16 opposing each other.

Extension 15 has a pair of fingers 17 and 18 integral therewith and bent at right angles to the plane of side 11. It will be noted that while fingers 17 and 18 lie in parallel planes they are offset from each other. Similarly extension 16 is provided with offset fingers 19 and 20 generally similar to fingers 17 and 18 to form two pairs of fingers 17 and 19, and 18 and 20. These various fingers are provided with apertures 21 to 24 inclusive.

Bottom portion 10 has a tongue 25 cut out therefrom and extending upwardly perpendicular to and between sides 11 and 12 to form a magnetic pole piece. Opposing arms 17 and 19 have adjustably bolted thereto at apertures 21 and 55

23 a generally Z-shaped member 28 made up of pole piece portion 29, and portions 30 and 31. Mounting portion 31 is wide enough to overlie both fingers 17 and 19. This Z-shape member 28 is rigidly maintained in predetermined position upon fingers 17 and 19 and by bolts 33. The pole face of portion 29 of Z-shape member 28 is preferably of the same dimensions as the pole face of pole piece 25. Pole pieces 26 and 29 have disposed over them magnetizing windings 35 and 36 respectively.

15 Fingers 18 and 20 are adapted to support the stationary contacts and movable portion of the system. Fig. 4 shows the entire movable portion 15 of the system and will now be described in detail. A pair of short spring members 38 and 39 operating as a unit are provided with apertures 40 and 41 at one end of each of said springs, this end being the rigidly clamped portion of the 20 spring. The other end of each of springs 38 and 39 are riveted at 42 and 43 at a rigid beam member generally designated by numeral 45.

25 This beam member 45 consists of a pair of side arms 46 and 47 extending downwardly from springs 38 and 39 and having an armature 49 connecting the free ends thereof. The top portions of side arms 46 and 47 have spring supporting portions 50 and 51 at which point the rivets 42 and 43 are located. These spring supporting 30 portions 50 and 51 extend toward each other and merge into a central beam portion 52 which may be curved or dished for strength. Beam portion 52 extends upwardly away from armature 49 and beyond the rigidly clamped end of springs 38 and 39. Beam portion 51 may be shaped in any suitable 35 fashion and preferably tapers to a contact supporting portion 54 carrying contacts 55 and 56 on opposite sides thereof.

40 So far the mass of the beam as a whole is concentrated above the light frame of which the armature forms a part. In order to stabilize the operation of the vibratory system and to control the dwell of the movable contact against the stationary contacts a supplementary spring system is provided. At 57 the beam spreads sideways 45 and has attached thereto springs 58 and 59 extending beyond the movable contacts 55 and 56. A weight 60 is carried by the top ends of springs 58 and 59.

45 Normally the entire vibrating element is not stiffly mounted if the stationary contacts are not considered. It is clear that unless the stationary contacts are hit, the resonant frequency of the beam structure is substantially due to supporting springs 38 and 39. This may be of the order of 50 to 100 cycles per second in a vibrator for commercial use in an automobile radio. The springs 58 and 59 are considerably stiffer than 38 and 39 and at frequencies of 50 or 100 cycles per second 55 may be considered as rigid members. It is only at higher frequencies that the energy stored in weight 60 is sufficient to utilize the resilience of springs 58 and 59 and control the dwell of the contacts. Under certain conditions, springs 58 and 59 may be prolongations of the beam proper.

60 The entire vibrating structure is clamped to the frame by suitable bolts 61 passing through apertures 22 and 24 of fingers 18 and 20 through apertures 41 and 40 of the vibrating portion of the system. It will be noted that springs 38 and 70 39 are disposed directly against the faces of fingers 18 and 20 respectively and thus are in good magnetic and electrical contact therewith. Disposed around bolts 61 are insulating sleeves 63 and 64 on opposite sides of the spring and finger metal portion.

75 A pair of stationary contact support members 65 and 66 are disposed on bolts 61 beyond insulating sleeves 63 and 64. These stationary contact members are similar and as shown in Fig. 5 comprise a supporting bridge portion 67 having apertures 68 and 69 at the ends thereof adapted to be threaded by bolts 61. It will be noted that apertures 68 and 69 are substantially larger than the diameter of each of the bolts and are so disposed as to be clear of the bolt.

10 From the center of the supporting portion 67 of the stationary contact member, an arm 70 extends upwardly and terminates in a contact supporting portion 71 upon which is mounted a stationary contact 72. The other corresponding 15 contact is 72'. A terminal lug 73 is provided for making connection to the stationary contact supporting member 67. Beyond each of the stationary contact supporting members 65 and 66 are insulating sleeves 74 and 75 slidably mounted on 20 bolt 61. Beyond these sleeves 74 and 75 are cross-bar members of metal 76 and 77 extending across bolts 61 and forming a rigid bridge.

25 Nuts 78 and 79 on the two bolts 61 hold the entire stack rigid. Bridge members 76 and 77 are provided with stiff upwardly extending massive portions 80 and 81 normally registering with portion 70 of the movable contact of the stationary contact member 67. Portions 80 and 81 are each provided with adjusting screws 82 and 83 having insulating tips 82' and 83' respectively. 30 Screws 82 and 83 with their lock nuts 84 are adapted to bear heavily against arm portion 70 below stationary contact 72 and thus in effect to form a stiff spring mounting for the stationary contact.

35 It will be noted that the ends of core members 25 and 29 are offset from each other and that normally armature 49 is disposed between the two opposing pole faces. Frame 45 has its side 40 arms 46 and 47 disposed just beyond the boundaries of coils 35 and 36 and is adapted to operate in the space between these coils and the inside surface of the frame itself. Substantial latitude in the normal idle position of the armature between pole faces is permissible.

45 Windows 13 and 14 in side arms 11 and 12 of the frame are normally adapted to register with the pole faces and armature 49 so that proper adjustment may be made.

50 Preferably the entire movable system is made of iron or steel and is highly magnetic. Since this movable portion of the system is directly carried by the upper portion of the frame it is clear that the armature 49 is coupled somewhat more closely to the upper magnetic circuit than it is to the lower magnetic circuit. In the normal operation of the vibrator both magnetizing coils 35 and 36 are simultaneously energized when the contacts are both open, and with armature 49 being disposed midway between the opposing pole faces, there will be a tendency for armature 49 to be attracted toward pole piece 29.

55 It is understood of course that with the exception of the armature, the entire vibratory portion may be made of non-magnetic metal. The effect of this will be to alter the coupling between the armature and magnetic circuits.

60 Referring now to Fig. 6, magnetizing coils 35 and 36 have one end connected to a line 90 grounded to the entire vibrator. Line 90 is connected through a battery 91 to 92 the midpoint of a transformer primary 93. Coils 35 and 36 are connected to contacts 72 and 72' respectively and then to the outer terminals 95 and 96 of halves 94 and 94' of the primary winding. Sec- 75

ondary 96 may feed the stepped up alternating currents to any suitable load here shown diagrammatically as a condenser 97 and resistance 98.

5 For proper starting, it is necessary to connect coils 35 and 36 so that opposite poles will be produced at the pole faces. Due to magnetic eccentricity the armature becomes polarized and is pulled by one pole and pushed by the other 10 toward one pole face. In some cases, it will be attracted toward the upper face and in other instances toward the lower, depending upon the properties and dimensions of materials. After starting, reversal of one coil will not generally 15 result in stoppage. It is preferred to retain the coils in their original proper relationship.

The lack of magnetic symmetry at the start of vibrator operation results in the armature being pulled in one direction. This unbalanced 20 force is sufficient for starting purposes but appears to have no substantial effects on the operation thereof. It is believed that the unbalanced starting force is too small in comparison to the forces created during vibrator operation to have 25 any substantial effect. Hence, after starting, the vibrator appears to operate in a thoroughly symmetrical manner.

Referring to the vibrating portion of the system shown in detail in Fig. 4, while springs 38 30 and 39 are shown as separate, it is evident that they may be integral with each other. It will therefore be apparent that when the expression "a spring" is used in the claims, it is to be understood as meaning a single spring as the result of 35 combining springs 38 and 39 into one or duplicate separate springs as shown in Fig. 4.

It is to be understood that springs 58 and 59 may be replaced by one spring and this may be disposed anywhere along the rigid beam, due to 40 the high degree of coupling furnished by the beam. The reeds 38 and 39 are the most flexible of the various springs. It is preferred to have springs 58 and 59 more flexible than the elastic mounting for the contacts. With regard to the 45 contact mounting, it is obvious that either the fixed or the movable contact may be mounted on a stiff spring, or both may be so mounted.

What is claimed is:

1. In a vibrator, a base, a pair of flat reeds 50 rigidly mounted on one of the ends thereof on said base, a rigid elongated beam mounted on the other ends of said reeds, an armature carried by said beam at one end thereof and a movable contact mounted on the other end thereof, 55 a stationary contact mounted on said base, at least one of said mounting means having a higher resonant frequency than said reeds, a spring carried by said beam at the contact end and extending beyond the contact and being stiffer than said reeds, a weight carried by said spring, an electro-magnet mounted on said base, said electromagnet including a magnetizing coil and pole face in proximity to said armature, and contact and magnetizing coil connections for maintaining 60 said reed in vibration upon circuit energization.

2. The structure of claim 1 wherein the armature is mounted at one end of said beam with the reeds secured at an intermediate point of said 65 beam.

3. In a vibrator, a base, a pair of flat reeds rigidly mounted at one of the ends thereof on said base, a rigid elongated beam mounted at the other ends of said reeds at an intermediate 75 portion thereof, an armature carried by said

beam at one end thereof and a movable contact on the other end thereof, a fixed contact on each side of said beam for alternate cooperation with said movable contacts, means for mounting said movable contacts on said beam, means for 5 mounting said stationary contacts on said base, one of said mounting means having a higher resonant frequency than said reeds, a spring carried by said beam at the contact end and extending beyond the contact and being stiffer than said reeds, a weight carried by said spring, an electro-magnet mounted on said base, said electro-magnet including a magnetizing coil and a pole face in proximity to said armature, and contact and magnetizing coil connections for maintaining 10 said reed in vibration upon circuit energization.

4. The structure of claim 3 wherein the mounting means for the stationary contacts have elasticity and wherein the movable contacts are rigidly mounted on said beam.

5. In a vibrator, a base, a pair of flat reeds rigidly mounted at one of the ends thereof on said base, a rigid elongated beam mounted at the other ends of said reeds, an armature carried by said beam, movable contacts rigidly mounted on said beam, a fixed contact on each side of said beam for alternate cooperation with said movable contacts, means for mounting said fixed contacts on said base, said mounting means 25 having a higher resonant frequency than said reeds, a spring stiffer than said reeds and a weight carried by said beam at the movable contact end thereof, an electro-magnet mounted on said base, said electro-magnet including a magnetizing coil and a pole face in proximity to said armature, and contact and magnetizing coil connections for maintaining 30 said reed in vibration upon circuit energization.

6. The structure of claim 5 wherein the armature is mounted at one end of said beam with the reeds carrying said beam at an intermediate portion thereof.

7. In a vibrator, a base, a pair of flat reeds rigidly mounted at one of the ends thereof on said base, a rigid elongated beam mounted at the other ends of said reeds, an armature carried by said beam, movable contacts on said beam, a stationary contact on each side of said beam for alternate cooperation with said movable contacts, 45 means for mounting said movable contacts on said beam at an end thereof, means for mounting said stationary contacts on said base, one of said mounting means having a higher resonant frequency than said reeds, a spring stiffer than 50 said reeds and a weight carried by said beam at the movable contact end, a pair of electro-magnets mounted on said base, each electro-magnet including a magnetizing coil and a pole face, said pole faces being disposed opposite each other with 55 the armature between them and adapted to vibrate back and forth between the opposed pole faces, and contact and magnetizing coil connections for initiating and maintaining reed vibration, said connections providing opposite polarities for the opposed pole faces.

8. The structure of claim 7 wherein the armature is mounted at one end of the beam with the beam carried by said reeds at an intermediate point thereof.

9. The structure of claim 7 wherein said beam is mounted on an intermediate portion thereof on said reeds with the armature at an end of said beam and wherein each of said magnetizing coils is shunted across a pair of cooperating contacts.

10. In a vibrator, a base, a pair of flat reeds rigidly mounted at one of the ends thereof on said base, a rigid elongated beam mounted at the other ends of said reeds, an armature carried by said beam, movable contacts rigidly carried on said beam, a stationary contact at each side of said beam for alternate cooperation with said movable contact coil, means for mounting said stationary contacts on said base, said mounting means having a higher resonant frequency than said reeds, said movable contacts being mounted at an end of said beam, a spring stiffer than said reeds and a weight carried by the contact end of said beam, a pair of electro-magnets mounted on said base, each electro-magnet including a magnetizing coil and a pole face, with said pole faces being disposed opposite each other and the armature between them and adapted to vibrate back and forth between the opposed pole faces, contact and magnetizing coil connections for initiating and maintaining reed vibrations, said connections providing opposite polarities for the opposed pole faces.
11. The structure of claim 10 wherein said beam is carried on an intermediate portion thereon with the armature mounted at one end thereof.
12. In a vibrator, a base, a pair of reeds, means for mounting said reeds rigidly on said base in spaced parallel relationship, a rigid elongated beam carried by the other end of said reeds at an intermediate point of said member, an armature carried by one end of said beam, movable contacts carried by the other end of said beam, a spring and weight carried by the contact end of said beam, stationary contacts carried by said base for alternate cooperation with said movable contacts, resilient means for mounting said stationary contacts on said base, said reeds being substantially less stiff than either said spring or said resilient contact mountings, at least one electro-magnet having a pole face in proximity to said armature, and contact and magnetizing coil connections for initiating and maintaining reed vibration.
13. The structure of claim 12 wherein a pair of electro-magnets are provided each having a pole face in opposed relation to the other with the armature therebetween.
14. In a vibrator, a U-shaped frame having a bight and sides, a pole piece extending from said bight up between said sides, a second pole piece supported on said frame and extending toward the first, said pole pieces terminating in staggered faces, a magnetizing coil for each pole piece, a pair of reeds rigidly clamped at the ends thereof to said frame, a rigid beam carried by said reeds at their other ends, said beam extending down toward the bight and terminating in an armature between the opposed pole faces, movable contacts mounted on said beam, stationary contacts mounted on the free ends of said frame for cooperation with said movable contacts, and connections between said contacts and coils for vibrating said reed.

HENRY M. DRESSEL.
